[57] **CLAIM**

I claim the ornamental design for a handle for a steam hair care implement, as shown.

DESCRIPTION

FIG. 1 is a right side elevational view of a handle for a steam hair care implement, the opposite side being a mirror image of the side shown;

FIG. 2 is a front end elevational view thereof;

FIG. 3 is rear end elevational view thereof;

FIG. 4 is a bottom plan view thereof; and,

FIG. 5 is a top plan view thereof.

The structures shown in broken lines are for illustrative purposes only and forms no part of the claimed design.

The interior surface inside the unshaded aperture in FIG. 2 forms no part of the claimed design.
